UNITED STATES PATENT OFFICE.

LLOYD M. MASEMORE, OF OLYMPIA, WASHINGTON.

ANÆSTHETIZER-TANK BRACKET.

Application filed March 31, 1925. Serial No. 19,643.

To all whom it may concern:

Be it known that I, LLOYD M. MASEMORE, a citizen of the United States, residing at Olympia, in the county of Thurston and 5 State of Washington, have invented certain new and useful Improvements in Anæsthetizer-Tank Brackets, of which the following is a specification.

The present invention relates to an anæsthetizer-tank bracket and has for its principal object to provide a bracket of this nature, which will be efficient and reliable in supporting tanks containing an anæsthetic gas used by dentists.

Another important object of the invention is to provide a bracket of this nature, which is supported on wheels, or casters, in order that it may be conveniently moved from place to place.

A further object of the invention is to provide a bracket of this nature, which is exceedingly simple in construction, strong, durable, easy to manipulate, not liable to readily get out of order, and otherwise well adapted to the purpose for which it is designated.

With the above and numerous other objects in view, as will appear as the description proceeds, the invention resides in certain novel features of construction, in the combination and arrangement of parts as will be hereinafter more fully described and claimed.

In the drawing:

Figure 1 is an elevation of the brackets embodying the features of my invention, portions being shown in vertical section.

Figure 2 is a top plan view thereof, showing the standard in transverse section.

Figure 3 is a detail perspective view of one of the jaws.

Referring to the drawing in detail, it will be seen that 1 designates generally the supporting structure which includes a plurality of radiating arms 2 having casters at the ends thereof attached thereto in the usual manner. The center of the supporting structure is provided with an internally threaded bore or opening 4, into which is threaded a tubular standard 5, for extending vertically. A leather washer 6 is disposed about the tubular standard 5, and rests on the supporting structure 1. A sleeve 7 is disposed about the standard 5, resting on the leather washer 6, and the upper portion of this sleeve is provided with external

threads. A cylindrical member 8 is threadably engaged on the upper threaded portion of the sleeve 7. A leather washer 9 is disposed between the upper edge of the cylindrical member 8 and the tubular standard 5. Two pairs of arms 10 radiate from the cylindrical member 8, the arms of each pair being vertically aligned, extending in parallel spaced relationship. One pair of arms is 60 diametrically opposed to the other pair of arms. A bolt 11 pierces the ends of the pairs of arms 10 and its head rests on the upper arm as is clearly illustrated in Figure 1, and a pin or like may be passed through the 65 lower end thereof, to prevent the pin from coming out of engagement with the arm.

A pair of jaws 12 are mounted on each pin 11. Each jaw 12 is provided with an apertured ear 13, which is thinner than the jaw, so that the jaws in each pair will swing in the same plane. The jaws are curved as is clearly shown in Figure 3, and provided intermediate their ends with slots 14, having a continuous flange 15 formed 70 thereabout. The opening and flange in one jaw of each pair is internally threaded, so that bolts 16 may be passed through the unthreaded opening 14 and have its threaded portion engaged with the threaded opening 80 14 of the opposite jaw, so that by turning this bolt, the jaws may be firmly clamped about an anæsthetizer tank, such as illustrated at 17. There are two pairs of jaws 12, on each pin 11, as is indicated to advantage in Figure 1 and also in Figure 2. The jaws on one side of each pin are disposed at a lower level than the jaws on the other side, as is evident from an inspection 85 of Figure 1.

It is thought that the construction, operation, and particularly the advantages of this invention will now be clearly understood and especially appreciated by dentists. The present embodiment of the invention, which I have described in detail, has been clearly disclosed by way of example, and it is apparent that numerous changes in the details of construction, in the sizes, in the proportions, in the materials, and in the combination and arrangement of parts may be resorted to, without departing from the spirit or scope of the invention as hereinafter claimed, or sacrificing any of its advantages.

Having thus described my invention, what I claim as new is:

1. In combination, a supporting structure,

a standard rising from the supporting structure, a sleeve resting on the supporting structure and disposed about the standard, a cylinder threaded to the upper end of the sleeve, a pair of arms projecting from the cylinder in vertical spaced relation, a pin extending through the ends of the arms, a pair of jaws pivoted to the pin, and a bolt engageable with the jaws for clamping them about a tank.

2. In combination, a supporting structure, a standard rising from the supporting structure, a washer disposed about the standard and resting on the supporting structure, a sleeve disposed about the standard and having its lower edge resting on the washer, a

cylinder threadably engaged with the upper end of the sleeve and disposed about the standard, jaws pivotally mounted on the cylinder, and means for clamping the jaws about a tank.

3. In combination, a standard, a sleeve rotatably disposed about the standard, a cylinder detachably connected to one end of the sleeve, a pair of arms projecting from the cylinder in vertical spaced relation, a pair of jaws pivoted between the extremities of the arms, and means for clamping the jaws about a tank.

In testimony whereof I affix my signature.

LLOYD M. MASEMORE.
